UNITED STATES PATENT OFFICE

MOSES SCHREIBER, OF NEW YORK, N. Y., ASSIGNOR TO ALLENTOWN KNIT FABRICS COMPANY, OF NEW YORK, N. Y., A CORPORATION OF PENNSYLVANIA

DESIGN FOR A KNITTED FABRIC

Application filed December 21, 1929. Serial No. 33,876. Term of patent 7 years.

To all whom it may concern:

Be it known that I, MOSES SCHREIBER, a citizen of the United States, residing at 564 West 160th Street, New York, city, borough of Manhattan, county and State of New York, have invented a new, original, and ornamental Design for Knitted Fabric, of which the following is a specification, reference being had to the accompanying drawing, forming part thereof.

The figure illustrates a piece of knitted fabric, showing my new design. The unit of the design is defined by the intersections of the diagonal lines designated ab—ab, with the diagonal lines cd—cd. The said unit of the design is repeated throughout the extent of the fabric in the relation shown.

I claim:

The ornamental design for a knitted fabric substantially as shown and described.

MOSES SCHREIBER.
